(57) **CLAIM**

The ornamental design for a double door crate cover, as shown and described.

DESCRIPTION

FIG. 1 illustrates an angled, front perspective view of a double door crate cover in a closed position;

FIG. 2 illustrates a top view of a double door crate cover;

FIG. 3 illustrates a right side view of the panels of a double door crate cover in the closed position;

FIG. 4 illustrates a rear view of a double door crate cover;

FIG. 5 illustrates a front view of the panels of a double door crate cover in the closed position;

FIG. 6 illustrates a left side view of the stationary panels of a double door crate cover;

FIG. 7 illustrates a top view of a double door crate cover that shows the front and right side panels in the open position;

FIG. 8 illustrates a top view of a double door crate cover that shows the front and right side panels in the open position;

FIG. 9 illustrates a right side view of a double door crate cover that shows the front and right side panels in the open position;

FIG. 10 illustrates a rear view of a double door crate cover that shows the rear stationary panel;

FIG. 11 illustrates a front view of a double door crate cover that shows the front panel in the open position; and,

FIG. 12 illustrates a left side view of a double door crate cover that shows the left stationary panel.

The broken, dashed lines shown in the various figures depicting embodiments of the invention are included for the purpose of illustrating environment and do not form any part of the claimed design.
